Patented Dec. 5, 1916.

UNITED STATES PATENT OFFICE.

HARPER E. STRATTON, OF EMPIRE, OHIO.

PIPE-CUTTER.

1,207,339.

Specification of Letters Patent.

Patented Dec. 5, 1916.

Application filed December 30, 1915. Serial No. 69,304.

To all whom it may concern:

Be it known that I, HARPER E. STRATTON, a citizen of the United States of America, and resident of Empire, county of Jefferson, 5 and State of Ohio, have invented certain new and useful Improvements in Pipe-Cutters, of which the following is a specification.

This invention relates to pipe cutters, and 10 it has for its primary object to provide a pipe cutting tool embodying a pair of cutting disks which are so disposed that each performs its share of the cutting function.

It is the purpose of the present invention 15 to provide a tool having companion disks the cutting action of which is substantially uniform or equal, the rearmost or trailing disk serving to cut into the pipe to an extent practically equal to that of the foremost disk.

A further object of the invention is to provide, in a device of the character mentioned, a pressure-applying roller which is so formed that the cuttings are not rolled 25 back into the incision produced by the cutters.

With these and other objects in view, the invention resides in the features of construction, arrangement of parts and combinations 30 of elements which will hereinafter be fully described, reference being had to the accompanying drawings, forming a part of this specification, in which—

Figure 1 is a side elevation of the invention; Fig. 2 is an enlarged side elevation of the yoke with the cutting disks mounted therein; Fig. 3 is a front view of the same; Figs. 4 and 5 are enlarged sections taken respectively on lines 4—4 and 5—5, 40 Fig. 1; and Fig. 6 is an enlarged detail section showing the swivel-like mounting for the adjusting screw.

Referring to said drawings, in which like designating characters distinguish like parts throughout the several views—1 indicates a curved jaw having a shank 2 which carries upon its rear end a heel portion 3, said parts being preferably formed integral. Embracing the shank 2 and slidably thereon is the 45 sleeve portion 4^a of a bearing block 4 in which is swiveled the front end of an adjusting screw or stem 5 which is threaded through the heel portion 3 and lies parallel to said shank 2. Said bearing block is adjustable with respect to the jaw 1 and has mounted in the upper front portion thereof

a roller 6 designed to engage a pipe 7 interposed between it and companion cutting disks 8 and 9 carried in aligned relation by said jaw. Said cutting disks are rotatably 60 mounted in an angular rocker or balance yoke 10 which is disposed within a suitable space provided therefor in said jaw, as in a recess or channel 11. Said balance yoke is of substantially V-shape and has its apex 65 or angle portion pivoted to said jaw, as shown at 13. The disks 8 and 9 are mounted in the ends or terminals of the opposite arms or members of said balance yoke and project from said jaw in a rearward direction for 70 presenting their peripheries to the pipe 7 interposed between said jaw and the roller 6. The channel 11 is of a depth sufficient to enable its side walls to extend beyond the cutting-disk journals, and also substantially 75 cover and shield the ends of the yoke.

As is obvious, forward adjustment of the bearing block 4, accomplished by forward turning of the adjusting screw 5, acts to thrust an interposed pipe against the peripheries or cutting edges of the disks 8 and 9. The engaged disks automatically adjust themselves to seat with equal pressure against the pipe, due to the balanced character of their mounting, and, consequently, 80 to cut into said pipe to a substantially identical extent. Upon rotation of the tool with respect to the pipe, the rearmost disk 9, or the disk occupying the position nearest the point of the jaw, follows in the cut or groove 85 produced by the foremost disk 8 and produces a cut equivalent to that of said foremost disk.

To prevent the roller 6 from rolling cuttings into the cut or incision, the same is 90 provided with a peripheral groove or channel 12 which is so positioned that said incision is straddled.

While the bore of the heel portion 3 through which the adjusting screw 5 is directed may be threaded in the usual manner, I prefer to have the same unthreaded and to seat a removable block 14 in a recess 15 in the front face of said heel portion, such block having a threaded bore therein 100 in which said screw is received. Thus wear occurs in the block instead of in the heel portion. As is apparent, the block may be replaced at slight expense when occasion 105 requires. The block 14 and recess 15 may 110 be of slightly tapered forms adapting the former for assuming dove-tailed seating re-

lation to the heel portion, as shown. Suitable means, as a set-screw 16 directed into impinging relation to the block 14, is employed for maintaining the latter against 5 chance displacement.

As a simple means of swiveling the front end of the adjusting screw 5 in the bearing block 4, I prefer, in order to render said screw readily removable, to provide an annular groove 17 in said screw adjacent to its front end, to seat said front end in a plain socket 18 in said bearing block, and to direct a set-screw 19 into said block at right angles to said adjusting screw with 10 its point loosely seated in said groove, as shown in Figs. 1 and 6.

Suitable stops, as pins 20, are provided in the recess or channel 11 at suitable points adjacent to the outer edges of the members 20 of the rocker or balance yoke for limiting the extent of rocking movement of the latter.

What is claimed is—

1. In a pipe cutter, a recessed jaw, a V-yoke pivoted at its apex in the jaw recess, a 25 cutting disk journaled on each of the other ends of the yoke, the side walls of the recess extending over the ends of the disk-journals and nearly to the extremities of the yoke, so that they substantially cover and shield the 30 yoke-arms from injurious impacts, a pair of

pins in the recess of the jaw to engage the yoke at its opposite sides to limit the swinging movement thereof, and means to hold a pipe in engagement with said disks.

2. In a pipe cutter, a jaw having a shank 35 and a heel, cutters borne by the jaw, said heel having a dovetailed recess opening through the front thereof, a dovetailed block removably fitted in the recess, said block and heel having registering threaded openings, a screw in said threaded openings, means operated by the screw to hold a pipe in engagement with the cutters, and means to hold the block against movement. 40

3. In a pipe cutter, a jaw having a shank 45 and a heel, cutters borne by the jaw, said heel having a recess, a block removably fitted in the recess, means to hold the block in the recess, said block and heel having registering threaded openings, a screw in said 50 threaded openings, and means operated by the screw to hold a pipe in engagement with the cutters.

In testimony whereof, I affix my signature in presence of subscribing witnesses.

HARPER E. STRATTON.
